UNITED STATES PATENT OFFICE

JULLIEN F. WINNEMORE, OF CHEVY CHASE, MARYLAND

DESIGN FOR A COMBINATION RECEPTACLE FOR SMOKERS' ARTICLES OR SIMILAR DEVICE

Application filed July 11, 1932. Serial No. 44,305. Term of patent 3½ years.

To all whom it may concern:

Be it known that I, JULLIEN F. WINNEMORE, a citizen of the United States of America, and resident of the city of Chevy Chase, county of Montgomery, and State of Maryland, have invented a new, original, and ornamental Design for a Combination Receptacle for Smokers' Articles or Similar Device, of which the following is a specification, reference being had to the accompanying drawing, forming part thereof.

The figure is a plan view of a combination receptacle for smokers' articles or similar device showing my new design.

I claim:

The ornamental design for a combination receptacle for smokers' articles or similar device substantially as shown.

JULLIEN F. WINNEMORE.
